UNITED STATES PATENT OFFICE.

JOHN EDWARD LELAND, OF MONTPELIER, VERMONT.

FILM-CLEANER.

1,165,265.

Specification of Letters Patent. Patented Dec. 21, 1915.

Application filed March 19, 1915. Serial No. 15,553.

To all whom it may concern:

Be it known that I, JOHN E. LELAND, a citizen of the United States, residing at Montpelier, in the county of Washington 5 and State of Vermont, have invented a new and useful Film-Cleaner, of which the following is a specification.

This invention relates to a device for cleaning and softening moving picture films 10 whereby dust, grease and the like may be quickly and efficiently removed without the use of a brush or other object which tends to scratch the film.

A further object is to provide a device of 15 this character which is simple and compact in construction and which can be manipulated readily.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, can be made within the scope of what is claimed, without departing from the spirit of the invention.

In the accompanying drawings the preferred form of the invention has been shown. 30 In said drawings:—Figure 1 is a vertical longitudinal section through the film cleaner, a film being shown in section in position therein; Fig. 2 is a side elevation of the film cleaner; Fig. 3 is a section on line 35 A—B Fig. 2; Fig. 4 is an elevation of the inner face of one of the members of the film cleaner, the cleaning pad being removed; Fig. 5 is a like view of the inner face of the other member of the cleaner with 40 the pad removed therefrom.

Referring to the figures by characters of reference 1 designates the bottom plate of the cleaner, the same being provided with openings 2 for the reception of fastening 45 screws 3 or the like, whereby it can be secured readily to a table 4 or other support. The bottom of the plate 1 is preferably hollowed out or reduced so as to lighten the structure and secured to this bottom plate 50 at one end is a spring catch 5 extending upwardly from the plate. An ear 6 is extended upwardly from the other end of the plate and receives a pintle 9 which extends through ears 10 extending from the top 55 plate 11 of the film cleaner. This top plate is adapted to be engaged by the spring

catch 5 as shown in Figs. 1 and 2. Formed within the inner face of the top plate 11 is a groove 12 with which communicates an opening 13 extending through the plate. 60 Another opening 14 is formed in the top plate 11 and is adapted, when the plate 11 is in its active position, to overhang the enlarged end 15 of a groove 16 formed in the inner face of the bottom plate 1. 65

Secured to one side of the bottom plate 1 is a spring clip 17 and another like clip 18 is secured to the same side of the top plate 11. These clips are adapted to engage the end portions of cleaning strips or pads 19 70 of felt or other suitable material, the width of these pads being substantially equal to the length of the groove 12 but the groove 16 being somewhat longer than the width of the pads. Thus it will be seen that when 75 the pads are in position, the groove 12 will be concealed whereas that end of the groove 16 having the enlargement 15 will project beyond one side of the pads.

In using the device the film to be cleaned 80 is placed on the lowermost pad 19 after which the upper plate 11 is swung downwardly into engagement with catch 5, thus to bring the upper pad 19 on top of the film. A suitable cleansing fluid is discharged into 85 the groove 12 through the opening 13 and another cleansing fluid is discharged through opening 14 into the enlargement 15, from which it will flow along the groove 16. Thus the two pads will become saturated with the 90 cleansing fluid and as the film is drawn between the two pads, it will be thoroughly cleaned thereby. The liquid can be supplied to the pads as needed, during the cleaning 95 operation by pouring it into the openings 13 and 14 so that it will thus be supplied to the two pads.

What is claimed is:—

1. A device for cleaning films, including 100 movably connected plates, there being a groove in the inner face of one of the plates provided with a feed opening and a groove in the inner face of the opposed plate, the first named plate having a feed opening for directing liquid into the last named groove, 105 and film engaging pads detachably connected to the plates and extending across the grooves, one end portion of said last mentioned groove, and its feed opening being located beyond the pads. 110

2. A device for cleaning films, including 110 relatively movable upper and lower plates,

said upper plate having a groove in its inner face provided with a feed opening and said lower plate having a groove in its inner face provided with an end enlargement, 5 there being a feed opening in the upper plate adapted to direct cleansing fluid into the enlargement, and cleaning pads connected to and interposed between the plates, said pads being removed from the enlarged

end of the lower groove and from the feed 10 opening provided therefor.

In testimony that I claim the foregoing as my own, I have hereto affixed my signature in the presence of two witnesses.

JOHN EDWARD LELAND.
